UNITED STATES PATENT OFFICE.

MARION A. WINGET, OF COLUMBUS, OHIO, ASSIGNOR TO ADDIE E. WINGET, ELI ROWLES, JOHN A. McDOWELL, AND J. MILAN McDOWELL, OF COLUMBUS, OHIO.

MACHINE FOR MOLDING CONCRETE BODIES.

SPECIFICATION forming part of Letters Patent No. 734,487, dated July 21, 1903.

Application filed April 11, 1903. Serial No. 152,169. (No model.)

To all whom it may concern:

Be it known that I, MARION A. WINGET, a citizen of the United States, residing at Columbus, in the county of Franklin and State of Ohio, have invented a certain new and useful Improvement in Machines for Molding Concrete Bodies, of which the following is a specification.

My invention relates to the improvement of machines for forming concrete blocks, and has particular relation to the improvement of that class of machines shown in my former patent, No. 694,123, issued under date of February 25, 1902.

The objects of my invention are to provide a simple, reliable, and effective machine for the formation of concrete or artificial-stone blocks for building or other purposes; to provide in connection with my machine improved means for regulating the extent of vertical movement of the hopper; to provide for an adjustment of the width of the hopper, whereby blocks of different widths may be produced; to provide improved means in connection with the frame of my machine whereby the machine may be rocked to a convenient angle for charging the hopper or ramming the material therein, and to produce other improvements, the details of which will be more fully pointed out hereinafter. These objects I accomplish in the manner illustrated in the accompanying drawings, in which—

Figure 1 is a side elevation of my machine with the hopper in a lowered position. Fig. 2 is a plan view. Fig. 3 is a central vertical section on line xx of Fig. 10. Fig. 4 is an enlarged sectional view through one of the yoke projections on the side of the hopper bottom plate, said view being taken on line yy of Fig. 5. Fig. 5 is a front elevation of the same. Fig. 6 is a view in elevation of one of the hopper-supporting yoke-frames. Fig. 7 is a view in elevation at right angles with that shown in Fig. 6. Fig. 8 is an enlarged transverse section on line zz of Fig. 6 with the yoke removed. Fig. 9 is a similar view showing the yoke-frame in connection with the bar shown in Fig. 8. Fig. 10 is an end view of my machine, showing the hopper in its elevated po-

sition and with its ends and sides thrown outward. Fig. 11 is a sectional view on line tt of Fig. 12. Fig. 12 is an enlarged view in elevation, illustrating the hinge connection of one of the end plates of the hopper with the body thereof; and Fig. 13 is an enlarged sectional view on line ss of Fig. 3.

Similar numerals refer to similar parts throughout the several views.

In carrying out my invention I employ a suitable framework comprising vertical end standards or uprights 1, which are connected at desirable heights by a horizontal frame-plate 2. Each of the frame-standards 1 is formed with a central vertical slot 3, and to the upper side of the frame-plate 2 are detachably secured the lower ends of upwardly-projecting cores 4. Above the frame-plate 2 I support in the manner hereinafter described a horizontally-disposed hopper bottom plate 5, said hopper further consisting of side and end plates 6 and 7, which are hinged in the manner hereinafter described. With the under side of the hopper bottom plate 5 and near each end thereof is connected the upper end of a vertical supporting-standard 8, each of these standards extending through a slotted opening 2^a in the plate 2 and having its lower end connected with a transverse rod or shaft 9, the end portions of which extend through the slotted openings 3 of the frame-standards 1.

10 represents yoke or U-shaped frames, with the centers of the lower or cross bars of which are connected rigidly the lower ends of the standards 8, the rod 9 thus piercing both said standards and yokes. The upwardly-extending arm 10^a of each of the yokes 10 is formed with a flaring head 10^b, on one face of which is provided a series of notches 11. At the junction of each of the arms 10^a and the cross-arm of the yoke 10 is pivoted an upwardly-extending bar 12 of greater height than the arms 10^a, said bars having their upper end portions bifurcated, as indicated at 12^a, and having said bifurcated portions pivotally connected with downwardly-projecting lugs 13 of the side plates 6 of the hopper. (See Fig. 1.) Each of the bars

12 has formed therein a transverse slot 12^c, through which projects a bolt 14, which extends from the head of the adjoining yoke-arm 10^a, this bolt being adapted to receive a nut on its outer end. Each of the bars 12 has, as indicated more clearly in Fig. 8 of the drawings, formed on that side which is adjacent to the adjoining yoke-arm 10^a a projecting tooth or lug 10^c, which, as indicated in Fig. 9, is adapted to engage the desired one of the notches 11 of said adjacent yoke-arm.

In the manner above described a hinge connection of the hopper side plates with the bars 12 of the supporting-yoke 10 is effected.

15 The end plates 7 of the hopper are hinged in connection with the ends of the bottom plate 5, each of said end plates being provided in its lower portion with projecting hinge-lugs 15, which are mounted on short hinge-pins 20, which are journaled between the sides of yoke-like projections 17 of the ends of the bottom plate 5. (See Figs. 11 and 12.) Through a threaded opening in the outer bar 17^a of each of said yoke-like projections extends a set-screw 18, the inner end of which is adapted to bear against the outer side of a downward extension 15^a of the hinge-lug 15, said set-screw or bolt thus serving to limit the inward movement of the hopper end 25 plate. The hopper end plates, which are thus hinged in their lower portions to the plate 5, are formed with an outwardly-projecting central rib 7^a, the lower portion of which is reduced in thickness, as indicated in the drawings. This rib is adapted to bear vertically against a roller 19, journaled in a bracket 20, these brackets being adjustably mounted upon the upper sides of the end portions of an oblong frame 21, mounted upon 30 the upper ends of the standards 1 and adapted to loosely embrace the hopper-body. In a similar manner outwardly-projecting ribs 6^a of the hopper side plates are adapted to contact with friction-rollers 22, mounted in 35 bracket-plates 23, adjustably connected with the frame 21. I also provide the bottom plate 5 on its longer sides with yoke-like projections 24, into which project downwardly-extending fingers 25 of the side plates 6^a. Running through a threaded opening in the outer bar 24^a of each of the yoke projections 24 is a set-screw 27, the inner end of this set-screw adapted to contact with one of the downwardly-projecting fingers 25 of one of said 40 side plates.

55 Journalled in the frame-standards 1 beneath the frame-plate 2 and at one side of the center of the width of the machine is a shaft 28, this shaft carrying on each of its ends a 60 gear-wheel 29 and on the inner side of said gear-wheel a pinion 30. These gear-wheels 29 have their upper sides in mesh with pinions 31, carried on the outer end portions of an upper horizontal shaft 32, which is also 65 journalled in the frame-standards 1 and which shaft is provided with crank-handle termina-

tions 33. On the inner side of one of the pinions 31 may be carried, as indicated in Fig. 1 of the drawings, a ratchet-wheel 34, with which is adapted to engage the toothed end 70 of a suitable pivoted pawl 35, this pawl serving when not thrown upward and out of engagement with the ratchet to prevent a reversed rotation of the shaft 32. The teeth of each of the pinions 30 engage the teeth of a 75 rack-bar 36. One of these rack-bars is arranged to slide vertically on the outer side of each of the end frames 1 over the slotted opening 3, said rack-bar being connected through the medium of bolts 37, extending through 80 said slotted opening, with a vertical plate or bar 38 on the inner side of the frame-standard and also being connected with the shaft or rod 9. As indicated more clearly in Fig. 13 of the drawings, each of the frame-standards 1 has formed on opposite sides of its slotted opening 3 inwardly-projecting vertically-arranged flanges or wings 39, the latter being formed, as shown more clearly in Fig. 3, with pin-holes 40, arranged one above the 85 other therein. In order to facilitate the movement of the inner bars 38 through the frame-plate 2, I recess the ends of said plate, as indicated at 41.

Within the hopper-body and upon the bottom plate 5 I support a mold-board 42, the latter being removable and formed with openings to receive the cores 4.

In constructing each of the standards 1 I form the under side thereof on a rocker-like 100 curve, as indicated at 1^a in Fig. 10, the rear portion of this curve terminating in a downwardly-extending leg portion 1^b, which is adapted to bear upon the ground or floor. At the forward sides of the frame I provide in 105 place of the legs 1^b legs 43, which are pivoted in their upper portions at 44 to the frame-standard, said pivoted legs being connected in their lower portions by a transverse connecting or trip rod 45. As indicated in Fig. 110 10 of the drawings, these pivoted legs 43 extend when in their normal positions below the frame-standards to a corresponding level with the legs 1^b; but when said legs 43 are turned outward on their pivots to the position indicated in dotted lines in Fig. 10 it will be observed that the side or edge of each of said legs, which becomes the under side, forms a continuation of the curvature of the portion 1^a of the standard, thereby permitting the 115 machine to be rocked forward and supported at such angle as to greatly facilitate the filling of the hopper and ramming of the material therein.

120 It will be understood that when the pinions 30 are in engagement with the upper portions of the racks 36 the hopper will be in its lowered position, the end plates 7 being held upright through the medium of the rollers 19, and the side plates being likewise 125 held upright through engagement of their end portions with lugs 7^b of said end plates.

Assuming that said hopper is thus supported in its lowered position, the material from which the building or other block is to be produced is introduced into the hopper 5 through the open upper side thereof, said hopper being thus filled to the desired depth about the cores. By then rotating the shaft 32 and through the gear connections described imparting a rotary motion to the shaft 28 and pinions 30 the engagement of said pinions with the rack-bars 36 will result in the lifting of the rack-bars and through the consequent lifting of the rod 9 and the supports 8 in an upward movement of the hopper body. 10 It is obvious that when the friction-rollers 19 are in contact with the lower portions of the end-plate ribs 7^a said end plates may drop outward and downward and that the same is true of the side plates 6, these plates being 15 shown in their outer positions in Fig. 10 of the drawings. The sides and ends of the hopper being thus dropped outward, it will be obvious that the block previously formed within the hopper will thus be exposed and 20 that said block will have been formed with openings therethrough conforming to the shapes of the cores 4. It will also be understood that the mold-board may be removed, together with the block, the hopper turned 25 to its lowered position, and again filled with material. In this operation of lowering the hopper it will be understood that the side and end plates thereof will be again raised to vertical positions. Owing to the contact 30 of the extensions 15^a of the hinge-lugs 15 with the screws 18 the degree of inward movement or inclination of said hopper end plates may be regulated, this being also true with reference to the side plates 6 in view of the contact 35 of the extensions 25 thereof with the adjustable screws 27. It being desired to increase or decrease the width of the block to be produced, the nuts of the bolts 14 may be loosened and the teeth or projections 10^c of the bars 12 caused to engage new teeth or notches of the series 11 on the heads of the yoke-arms 10^b. It will be understood, however, that the change in the width of the block to be produced necessitates the employment 40 of a mold board or plate 42 of proper width.

In order to regulate the extent of the upward and downward movement of the hopper, I provide the frame flanges or wings 39, 45 having the openings 40 therein, through which may be inserted stop-pins, one of which is indicated at 48 in Fig. 13. These stop-pins are adapted by contact with the rod 9 to stop the movement of the rack-bars, and consequently 50 stop the movement of the hopper. The bearing of the set-screws 27 against the extensions 25 of the side plates also serves to strengthen said side plates against outward

movement which may be caused by pressure on the material contained in the hopper. 65

Having now fully described my invention, what I claim, and desire to secure by Letters Patent, is—

1. In a machine for molding concrete bodies, the combination with a framework, and a hopper comprising a bottom plate and side and hinged end plates, of a vertically-movable support for said hopper comprising a yoke-frame and bars pivotally and adjustably connected with said yoke-frame, said bars having hinge connections with said hopper side plates, for the purpose specified. 75

2. In a machine for molding concrete bodies, the combination with a framework comprising end standards having projecting flanges 80 provided with a plurality of pin-holes, a hopper comprising a bottom plate and side and end hinged plates, of a vertically-movable support for said hopper, rack-bars movably mounted on said end standards, a shaft connecting said rack-bars and carrying said hopper-support, said shaft adapted to contact with pins connecting opposite openings in said frame-flanges, for the purpose specified. 85

3. In a machine for molding concrete bodies, the combination with a framework, a hopper 90 vertically movable therein, hinged hopper side and end plates and a bottom plate for said hopper, said bottom plate having yoke-like projections as 24 and said hinged side 95 plates having extensions 25 extending within said bottom-plate projections, and set-screws adjustably supported in said bottom-plate projections, substantially as specified.

4. In a machine for molding concrete bodies, the combination with a hopper-supporting framework comprising connected end standards, the lower ends of said standards being curved to form a forward-rocking motion of the frame and means connected with the forward portions of said standard-bases for preventing a forward-rocking movement of the frame when not desired, substantially as specified. 105

5. In a machine for molding concrete bodies, the combination with a framework comprising connected standards 1 having curved under sides and having fixed leg projections on their rear portions, of legs 43 pivotally connected with the forward sides of said standards, said pivoted legs adapted to be projected downward to form forward supports for the frame, or to be swung outward and upward to form rocker-like continuations of the bases of said standards, substantially as specified. 115 120

MARION A. WINGET.

In presence of—

S. A. WEBB,

C. C. SHEPHERD.
